UNITED STATES PATENT OFFICE.

ERNST R. RICHARDS, OF CHICAGO, ILLINOIS.

INSERTING MACHINE.

Application filed March 17, 1921. Serial No. 453,033.

To all whom it may concern:

Be it known that I, ERNST R. RICHARDS, a citizen of the United States, residing at Chicago, in the county of Cook and State 5 of Illinois, have invented certain new and useful Improvements in Inserting Machines, of which the following is a specification.

The invention relates to the art of assembling signatures and has particular reference to a machine for automatically inserting single sheets in signatures.

An object of my invention is to provide a machine for inserting single sheets in signatures.

15 Another object of the invention is to provide a machine for automatically inserting single sheets in signatures in inset relation.

A further object of the invention is to provide a machine for inserting single sheets 20 in signatures in an efficient, expeditious and economical manner and which will be entirely automatic in operation.

With this end in view the invention consists of a machine having a hopper for holding 25 a supply of signatures and a hopper or a plurality of hoppers for holding supplies of single sheets, suitable mechanism being provided to withdraw a single article from every one of the several hoppers in timed relation and delivering the same at a common 30 point or zone wherein the single sheets may be inserted in a signature.

The form of the machine which I have chosen to illustrate my invention includes an 35 intermittently rotating drum or carrier having preferably a plurality of flat sides and delivery mechanism cooperating with the several hoppers so that a signature may be delivered onto one of the flat sides of the 40 drum and when the drum has been turned in a certain manner a sheet or sheets may be inserted in the signature on the drum.

The various novel features of my invention will be apparent from the following 45 description and drawings and will be particularly pointed out in the appended claims.

In the drawings:

Fig. 1 is a side elevation of a machine dis- 50 closing the preferred form of the invention.

Fig. 2 is an enlarged side view with parts 55 broken away showing certain details of construction.

Fig. 3 is an enlarged end view of a portion 60 of the machine showing the drum or reel in side elevation; and

Fig. 4 is an enlarged fragmentary view of the preferred means for opening a signature. The machine illustrated includes a base 5 with upright frame members 6 and a plurality of hoppers A, B and C suitably supported 60 on the frame.

Referring to Fig. 2 of the drawings certain details of construction will be clear. The hoppers which I have illustrated are similar in every respect and are arranged in 65 such a manner that an article withdrawn from one may be moved in timed relation with an article withdrawn from another and all brought together for the purposes intended. Every hopper includes an inclined 70 bottom 7, side guides 8 and a front guide 9. The forward end of the inclined bottom 7 is cut away or stops short of the front guide 9 so as to permit withdrawal of the bottom-most article in the hopper. The bottom 7 and the guides 8 and 9 are suitably supported on the frame members 10, 11 and 12, which are mounted on the frame members of the machine in such a manner as to be readily 75 removed, adjusted or replaced whenever the occasion demands. The bottoms 7 and the guides 8 and 9 are mounted for ready removal, on the frame members 10, 11 and 12 by means of looped ears 13 hooking over laterally extending projections 14 in the several 80 frame members the reason for such construction being that it may be necessary at times to vary the guides of the hoppers according to the sizes of the material being run through the machine and for other purposes 85 90 of adjustment and the like.

Mounted adjacent the lower ends of the inclined bottoms 7 of the several hoppers are transversely extending shafts 15 which carry withdrawing devices which in the form 95 shown are pneumatic devices comprising cylinders 16 with a plurality of radial apertures 17 extending from a central open portion to the surface, suitable means being provided to connect the members 16 with a suction device for the purpose of withdrawing the lowermost article in the several hoppers, as will be more fully explained.

Suitable mechanism is provided for accom- 100 plishing the withdrawing devices in timed relation with various other features of the machine.

As I have arranged the present machine 105 the hoppers B and C are adapted to contain piles of single sheets and are disposed 110

to discharge toward each other, although such disposition is not essential, but is so arranged for the purpose of decreasing the size of the machine. The hopper A which contains the signatures is arranged below and, as shown in the drawings, to the left of the hoppers B and C.

For conveying any article withdrawn from any of the hoppers to a common point or zone I have preferred to employ a series of endless tapes or aprons operated in a suitable manner for carrying out the purpose intended. Referring to Fig. 2 of the drawings it will be noted that the sheets from the hopper B are withdrawn by means of a suction device 16 and directed downwardly between the rollers 16 and 20 and, on to the curved guides 21 which contact the leading edge of the sheet at the instant the suction is cut off through the roller 16 and delivers the leading edge onto tapes 18 moving in the direction indicated by the arrow. The roller 16 is caused to rotate in clockwise direction until the following edges of the sheet is clear thereof, thereupon, by suitable mechanism the roller is turned in counter clockwise direction to the position shown in Fig. 2, ready as soon as the suction is created therein to withdraw the next, which is now the lowermost article, in the hopper. Overlying the tapes 18 are bars 18^b adapted to prevent the sheet from being displaced from the tapes 18 and which cause the sheet to follow the path of the tapes. After passing the roller 19' the tape has a downward path passing over the roller 19'' then upwardly over the intermediate roller 19''' back to the roller 19, immediately adjacent the suction roller 16. A sheet after passing the lowermost roller 19'' is freed from the tapes and passes downwardly, as will be hereinafter explained.

A sheet may be withdrawn from the hopper C in exactly the same manner as that described with reference to hopper B. If two sheets are to be withdrawn at one time from each of the hoppers for delivery to the common zone the delivery mechanism co-operating with each hopper will be operated in timed relation to carry out this purpose.

Signatures are piled in the hopper A with the folded edges to the front. I prefer to fold the signatures with an edge projecting at the place of insertion. In connection with the hopper A withdrawing devices 16 similar to those described with reference to hopper B are provided for withdrawing the lowermost signature in the hopper. The leading or folded edge of the signature is drawn downwardly between the rollers 16 and 20 and onto a curved guide 21^a, which frees the leading edge of the signature when the same has been freed from engagement by the suction roller 16 and directs the same onto tapes 67 moving in the direction indi-

cated by the arrow and supported on rollers 68, 68^a and 68^b. A top guide 69 is provided for keeping the signature on the tapes 67. Adjacent roller 68^a is another roller 70 which serves to bend downwardly the tapes 67 in the manner shown. The top guide 69 has its end bent to direct a signature on the tape 67 between the roller 68^a and 70. The signature is then led by means of the tapes 67 onto one of the flat sides of the carrier E, which as shown, is preferably in the form of a pentagon in section and which is supported by means of a transversely extending shaft 24 in the frame of the machine and which is caused to rotate in clockwise direction intermittently by mechanism hereinafter described. The length of the pentagon E is such as to take the largest signature of which the machine is capable of receiving. This feature is true of, course of all of the various elements of the machine.

The reference character 26 represents one of the sides of the pentagon and is referred to as the flat side which is in horizontal position to receive a signature from the tapes 67. Near the rearward edges of the several sides of the pentagon are a plurality of spring fingers or grippers 25 against which the leading or folded edge of the signature is delivered by the tapes. The parts are so arranged that as soon as a signature is delivered against the spring fingers 25 of the horizontal side of the pentagon the pentagon is given rotative movement in clockwise direction to the extent of one step which carries the signature from a horizontal position to an inclined position F, the clips or grippers 25 serving to pull the signature from the tapes 67.

It will be noted by reference to Fig. 2 that the tapes 18 and 18^b, moving as indicated by the arrows, come together at the lower rolls 19'' and 19''. Beside these tapes in this position are guide rods formed by members 28 and 28^a so as to receive and direct downwardly the sheets carried by the tapes. For opening a signature as the same is moved by the pentagon from the position 26 to F I have mounted a finger H in such position as to contact the signature and to bend back or retard the lower or projecting edge of the signature, permitting the shorter or upper edge to spring away from the lower half of the signature, opening the same a sufficient amount to receive a single sheet. In Figure 4 the withdrawal member or finger H is shown as being pivotally mounted on a stub shaft 80, which is suitably secured to the framework. A bracket 81 supported on the framework in any suitable manner is provided with spaced jaws 82 and 83 and has a bolt or similar member 84 passing therethrough. A spring 85 surrounds the bolt bearing against jaw 82 at one end and

against the end 86 of the finger H, the purpose of this construction being to yieldably maintain the finger H against the carrier E. In Figure 4 the opened signature F is shown 5 with one of its edges held between the foot of the finger H and the carrier E, indicated at 87. In operation as the carrier is rotated in its step by step movement the foot of the finger H will be frictionally held against 10 the carrier by the bracket and the spring 85 cooperating in the manner hereinbefore described. The signature being now in the position F of Fig. 2. A suitably supported guide finger 27 is provided for preventing 15 displacement of the signature from the inclined position on the pentagon and also for limiting the opening movement of the signature. After a sheet or plurality of single sheets have been inserted in the open signature 20 in the inclined position, as shown, the mechanism is operated to advance the pentagon one step.

The delivery mechanism associated with the hopper A has by this time delivered a second 25 signature onto the horizontal side of the pentagon and the delivery mechanism associated with hoppers B and C have withdrawn a sheet or plurality of sheets, as the case may be, and are conveying the same to the common zone 30 or point for delivery in insert relation with the signature then on the horizontal side 26 of the pentagon. The pentagon being moved the signature in the inclined position F is then moved to a lower inclined position 35 G whereupon the same falls off the pentagon and on to a conveyor "D" for further operations. As an aid in withdrawing the signature in the position "G" of the pentagon a shoe 29 carried by a link 30 supported 40 at the end of the arm 31 suitably mounted on shaft 24 may be provided and arranged to engage the following edges of the signature moving from the position F in Fig. 1. This engagement serves to pull the signature carrying its inserted sheets from engagement 45 with the fingers 25 and dropping the same onto the conveyor "D."

It will be noted that my machine will withdraw a signature from a hopper, open 50 the same, and automatically insert therein a single sheet or plurality of single sheets. The parts function in timed relation so that no manual operation is required other than that for keeping the hoppers A, B and C 55 filled, the first with signatures and others with piles of single sheets.

Fig. 1 shows somewhat diagrammatically the various connections for effecting timed 60 movement of the several elements employed in my invention. A transversely extending shaft 32 is adapted to receive power from any suitable source (not shown) and caused to rotate in clockwise direction. The shaft 32 carries a pinion 33 which meshes with

a large pinion 34 on shaft 35 suitably supported in the frame and which pinion meshes with pinion 36 from which pinion 36 by means of gear trains motion is imparted to the several units of the machine. The large gear 34 on the shaft 35 carries at 70 diametrically opposite points in its periphery laterally extending rollers 66. On the shaft 24 supporting the pentagon and outwardly thereof, so as to clear the several pinions and other mechanisms of the machine is a plate 75 which is also pentagonal in outline and which has formed on its inner sides a plurality of radially extending slots 76 so disposed with reference to the large pinion 34 as to be engaged by the rollers 66 80 thereon at certain points in the travel thereof.

As seen in Fig. 1 when the pinion 34 moves in counter clockwise direction the lower roller 66 will eventually engage the slot 76 shown in the position 76^a and by means of sliding contact rotate the pentagon one step in clockwise direction and will continue to rotate the same until the roller arrives at the position 76^b in Fig. 1, whereupon 90 engagement with slot 76 ceases and the plate and its shaft and drum come to rest. For preventing the pentagon from turning during the time the rollers 66 are out of engagement with the slots 76 I provide a member 95 34^a on shaft 35 having convexly curved ends 34^b which contact concavities 76^b in the end plate 75 of the pentagon. It will be noted that the pentagon is given step by step movement by what may be termed a Geneva motion. However, any other mechanism may be arranged to impart step by step motion to the pentagon timed with respect to the various other features of the machine.

As shown the tapes serving the various hoppers are means for bringing together the contents of the hoppers in a common zone or point, as hereinafter described. Reciprocal movement of a pneumatic suction cylinder 16 100 is accomplished by means of cranks and arms 71 and 72 cooperating with shafts 73 and 74, as clearly shown in the drawings.

It will be noted that an apparatus of my invention makes possible the inserting of a single sheet or a plurality of single sheets in a signature, something which has never been accomplished by any of the machines now on the market for inserting signatures. I am aware that many machines have been devised for inserting one signature within another and assembling a plurality of signatures for the purpose of binding. My machine differs from these machines in that it is adaptable for inserting single sheets in a signature or a plurality of single sheets in a signature and for no other purpose. In fact a signature after having had a single sheet inserted therein, must be submitted to

other operations for piling or inserting any other signatures and for the purpose of binding.

5 My invention is found particularly desirable for inserting a single sheet or a plurality of single sheets in a signature comprising two or more sections which have one folded edge, that is a signature comprising several sections which are open on three 10 edges and which are fed with the only closed or folded edge foremost. Such signatures are employed to a large extent in catalogue manufacture.

15 My invention is found particularly useful in making of catalogues where it is desirable to insert colored sheets or other kinds of data which could not have been printed in the same machine with the signature.

20 While I have described more or less precisely the details of construction of my invention, I do not wish to be understood as limiting myself thereto, as I contemplate changes in form and the proportion of parts and the substitution of equivalents as circumstances may suggest or render expedient, without departing from the spirit of my invention.

I claim:

30 1. In a mechanism of the class described, in combination, means for gripping a folded edge of a signature and moving the same along a predetermined path, means for engaging a free edge of said signature for opening the same, and means effective while 35 said signature is open and still gripped for inserting a single sheet therein.

2. In a mechanism of the class described, in combination, a supply of signatures, 40 means for withdrawing a signature from said supply, means for moving said signature, means for gripping a folded edge of said signature and moving the same along a predetermined path, means for engaging a 45 free edge of said signature for opening the same, and means for delivering an inset into said opened signature.

3. In a mechanism of the class described, in combination, a plurality of hoppers, a supply 50 of signatures in one hopper, a supply of inserts in another hopper, means for withdrawing a signature from said first hopper and moving it with a folded edge foremost along a curvilinear path, a finger arranged 55 to open said signature by frictionally contacting and retarding a portion of said signature as it is moved, means for withdrawing an inset from another hopper and delivering it into said open signature, and 60 other means adapted to release said signature with its insert from its path of movement.

4. In a mechanism of the class described, in combination, means for moving a signature, means including a finger effective dur-

ing the movement of said signature for opening the same by engaging and bending back an edge of the signature for receiving an insert, and other means effective after said signature has received an insert for releasing it from movement.

5. In a mechanism of the class described, in combination, a plurality of hoppers, a rotating flat sided carrier, means for imparting step by step movement to said carrier, means for delivering a signature from one hopper to said carrier, means for rotating said carrier one step, means effective during the said movement of said carrier for engaging and bending back an edge of the signature thereon, means for conveying the contents of another hopper into said open signature on said carrier in inset relation, and means for actuating the aforesaid means in timed relation.

6. In a mechanism of the class described, in combination, a plurality of hoppers, a rotating carrier, means for imparting step by step movement to said carrier, means for delivering a signature from one hopper to said carrier, means for rotating said carrier one step, means effective in the movement of said carrier for engaging and bending back an edge of the signature thereon, and means for conveying the contents of another hopper into said opened signature on said carrier in inset relation.

7. In an apparatus of the class described, having a signature hopper and a sheet hopper, including in combination the following 100 elements all operated in timed relation, a carrier, means for withdrawing a signature from said hopper, means for delivering said signature onto said carrier, means for rotating said carrier, means for opening the signature on said carrier, and means for delivering a single sheet into said opened signature.

8. In a machine of the class described, in combination, means for moving a signature flatwise and with a folded edge foremost, means operative during the movement of the signature for engaging and retarding a free edge of the lower part of the signature, and means for inserting a single sheet in said signature while the lower edge thereof is in retarded position.

9. In a machine of the class described, in combination, a plurality of signatures folded so as to have certain edges projecting, means for feeding a signature with a folded edge foremost, means for feeding a single sheet for insertion in said signature, and means for opening said signature to receive said sheet including a finger adapted to engage and bend back the projecting edge thereof.

10. In a machine of the class described, in combination, means for feeding a signature with a folded edge foremost, means

- for feeding a single sheet for insertion in said signature, means including a horizontally disposed five sided carrier for moving said signature into position to receive said sheet, means thereon for receiving said signature, means for rotating the carrier, and means adapted to contact a projecting edge of said signature for opening the same during the rotation of said carrier.
11. An improvement in the art of inserting sheets and the like in signatures, which consists in folding a signature with an edge projecting at the place of insertion, moving said signature, and during the movement thereof retarding said projecting edge for opening the signature, and then inserting a sheet or the like therein.
12. In an inserting machine, in combination, means for moving a signature, and means effective during the movement of said signature for engaging and bending back an edge of the same for receiving an insert.
13. In a mechanism of the class described, in combination, a plurality of hoppers, a rotating horizontally disposed carrier, means for delivering a signature flatwise to said carrier while the same is at rest, means for imparting intermittent rotative movement to said carrier, means effective during the movement of said carrier to open said signature, said means including a member for bending back an edge of said signature, and means for conveying the contents of another hopper to said opened signature on said carrier for assembly in inset relation.
14. In a mechanism of the class described, in combination, a plurality of hoppers, a horizontally disposed rotatable carrier, means for imparting step by step movement to said carrier, means for delivering flatwise a signature from a hopper to said carrier, means on said carrier for gripping said signature, means for rotating said carrier one step, means effective in the movement of said carrier for engaging and bending back an edge of the signature thereon, and means for conveying the contents of another hopper into said opened signature on said carrier while said signature is engaged by said grippers.
15. In an apparatus of the class described, including in combination the following elements all operated in timed relation, a horizontally disposed rotating carrier, means for withdrawing a signature from a hopper, means for delivering said signature flatwise on to said carrier, means on said carrier for gripping said signature, means for moving said carrier, means for opening the sig-
- nature while on said carrier, and means for delivering a single sheet into said opened signature.
16. In a mechanism of the class described, in combination, means for withdrawing and delivering a signature, means for gripping said signature by a folded edge and moving said signature in a curvilinear path, means effective during the movement of said signature for bending back an edge of the signature for opening the same and means for delivering insets into said opened signature.
17. In a machine of the class described, in combination, means for withdrawing and delivering a signature, means for gripping said signature by a folded edge and moving the same along a curvilinear path, a stop in the path of movement of said signature adapted to contact an edge thereof for opening the same, and means for delivering insets into said opened signature.
18. In a machine of the class described, in combination, a supply of signatures, means for withdrawing a signature from said supply, means for feeding said signature, means for gripping a folded edge of said signature and moving the same along a predetermined path, means for engaging a free edge of said signature for opening the same, means for delivering an inset into said opened signature, and means for disengaging said signature from said gripper after receiving said inset.
19. In a machine of the class described, in combination, means for delivering a signature flatwise with a folded edge foremost, means for gripping said folded edge for advancing said signature, means for opening said signature while the same is being advanced by said grippers, and means for delivering a single sheet into said opened signature, said opening means cooperating to keep said signature open for the reception of said sheet.
20. In a machine of the class described, in combination, means for delivering a signature flatwise with a folded edge foremost, means for gripping said folded edge for advancing said signature, means for opening said signature while the same is advanced by said grippers, means for delivering a single sheet into said opened signature, said opening means cooperating to keep said signature open for the reception of said sheet, and automatic means for actuating said above mentioned means.

Signed at Chicago, Illinois, this 5th day of March, 1921.

ERNST R. RICHARDS.
